(57) **CLAIM**

The ornamental design for a long handle toenail clipper, as shown and described.

DESCRIPTION

FIG. 1 is a perspective view of a long handle toenail clipper showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the long handle toenail clipper.

The broken lines in the drawings depict portions of the long handle toenail clipper that form no part of the claimed design.
